CONVEYER CHAIN

Fred. P. Noffsinger and Robert W. Noffsinger,
Greeley, Colo.

Application March 29, 1937, Serial No. 133,489

7 Claims. (Cl. 198—195)

This invention relates to a bar conveyer chain which, while more particularly designed as the elevating chain for potato diggers and the like, will be found useful wherever an open bar conveyer is required.

The principal object of the invention is to provide a bar conveyer construction which will be economical to manufacture and which can be easily and quickly assembled in any desired lengths without the use of tools.

Another object of the invention is to provide a bar conveyer construction which will be self-locking when assembled; long wearing; and in which worn or broken parts can be quickly and easily replaced while in the field.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:—

Fig. 1 illustrates a bar as employed in the invention.

Fig. 2 is a plan view of a portion of the assembled conveyer.

Fig. 3 is a perspective view of a conveyer link.

Fig. 4 is a side elevation of a section of the conveyer illustrating the method of assembling the same.

The invention comprises two series of links, such as illustrated in Fig. 3. These links each comprise a main link portion 10 carrying at one extremity a single centrally positioned bar loop 11, and at its other extremity a pair of similar spaced-apart bar loops 12.

At the center portion of the link, between the bar loops 12, is a sprocket notch 13, containing a sprocket bearing face 14.

The links are used in conjunction with a series of conveyer bars 15. The bars 15 may have any desired length, depending upon the width required for the complete conveyer.

The bars are offset, as shown at 16, adjacent each of their extremities and terminate in bearing ends 17 which are in axial alignment with the main portion of the bar. It is preferred to employ straight, round rods for the bar 15 to form the offset 16 by heating the extremities of the bars and deforming them in a punch press, thus insuring that all of the offsets will be uniform.

The width of the notch in the offset 16 is substantially equal to the width of the bearing loop 11 of the links, and the over-all width of the offset is substantially equal to the spacing between the two bar loops 12 of the links.

To assemble the chain, the offsets of one of the bars 15 is slipped into the bar loops 11 of a pair of links. A second pair of links is then turned upwardly, as shown at the right of Fig. 4, with their hooks 12 engaging each side of the offsets and are then turned downwardly into alignment with the first links. This is continued throughout the line of the links.

When the chain is completed the links are self-locking. The hooks 12 cannot unhook since the shoulders on the portion 10 strike the hooks 12 of the adjacent link, and similarly the hooks 12 cannot unhook since they strike the shoulders of the next link. Therefore, after the chain is once assembled, it is securely and permanently locked. However, should it be desired to remove a link or a bar, it can be done by turning the link at right angles to the bar and slipping the hooks from the bars.

The teeth of sprockets enter the sprocket notches 13 of the links and bear between the loop 11 of one link and the bearing surface 14 of the adjacent link. There are no bearing surfaces between the links themselves and all wear is confined to the bars 15 which can be easily replaced when necessary.

The links may be formed by drop forging or may be cast from malleable iron or steel.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:—

1. A conveyer chain consisting of a series of bifurcated links, the furcations at each side of the bifurcation being turned back upon themselves to form a pair of hooked extremities; a single bar loop at the opposite side of said link in alignment with the bifurcation therein; and an offset bar extending through the hooked extremity of one link, thence extending longitudinally of said chain between the latter hooked extremity and the bar loop of an adjacent link, thence extending laterally of said chain through the latter bar loop, thence returning longitudinally of said chain between said latter bar

loop and the other hooked extremity, thence passing through said latter extremity to connect the adjacent links together with said bar separating the hooked extremities from the bar loops thereof.

5. 2. A conveyer chain consisting of a series of bifurcated links, the furcations at each side of the bifurcation being turned back upon themselves to form a pair of hooked extremities; a single bar loop at the opposite side of said link 10 in alignment with the bifurcation therein; and an offset bar extending through the hooked extremity of one link, thence extending longitudinally of said chain between the latter hooked extremity and the bar loop of an adjacent link, 15 thence extending laterally of said chain through the latter bar loop, thence returning longitudinally of said chain between said latter bar loop and the other hooked extremity, thence passing through said latter extremity to connect the adjacent links together with said bar separating the hooked extremities from the bar loops thereof, 20 the bifurcations in said links extending inwardly therein beyond the position of said bars to form openings through the links for the reception of 25 sprocket teeth.

3. A bar conveyer comprising a series of round parallel bars; an offset formed in each bar adjacent each extremity thereof; a series of links; a single bar loop on one side of each link; double 30 bar hooks on the other side of each link, said single bar loops being engaged in the offset portions and said double bar loops engaging said bars at each side of said offset; and shoulders formed on said links to prevent the adjacent 35 links from unhooking, all of said loops having an open side, opening in the direction of the plane of said link there being an opening through each of said links for the reception of sprocket teeth.

4. A bar conveyer comprising a series of parallel bars; an offset formed in each bar adjacent each extremity thereof; a series of links; a single bar loop on one side of each link; double bar hooks on the other side of each link, said single 40 bar loops being engaged in the offset portions

and said double bar loops engaging said bars at each side of said offset; and shoulders formed on said links to prevent the adjacent links from unhooking, all of said loops having an open side, 5 opening in the direction of the plane of said link, so that when said links are turned to a position substantially at right angles with each other said loops may be slid from engagement with said bar and with said shoulders.

5. A link for bar conveyers comprising a relatively flat body portion; a bar loop extending from the mid-portion of one side of said body portion; and a pair of bar loops extending from the other side of said body portion, said links being bifurcated between said pair of bar loops 15 to form a sprocket tooth notch in said body portion.

6. A link for bar conveyers comprising a relatively flat body portion; a bar loop extending from the midportion of one side of said body 20 portion; and a pair of bar loops extending from the other side of said body portion, said pair being spaced-apart a distance sufficient to allow an offset bar to pass longitudinally between the pair of bar loops and the first bar loop and on 25 each side of the latter.

7. A bar conveyer comprising: a series of round parallel bars; a rectangular offset formed in each bar adjacent each extremity thereof, said offset consisting of a short section of said bar forced 30 to one side of the main section and connected with the main section by short lateral bends; a series of links; a single bar loop on one extremity of each link; a pair of spaced-apart bar loops on the other extremity of each link, said 35 single bar loops being engaged in the offset portions of said bars; and said pair of bar loops engaging the main portions of said bars at each side of said offset so that said bent portions will separate the single bar loops from the pair of 40 bar loops.
